UNITED STATES PATENT OFFICE.

ALBERT B. WEISSENBORN, OF APPLETON, WISCONSIN, ASSIGNOR OF ONE-HALF TO
APPLETON WIRE WORKS, OF APPLETON, WISCONSIN, A CORPORATION OF WIS-
CONSIN.

FOURDRINIER-WIRE STRETCHER.

1,272,586.

Specification of Letters Patent. Patented July 16, 1918.

Application filed April 8, 1915. Serial No. 20,070.

To all whom it may concern:

Be it known that I, ALBERT B. WEISSENBORN, a citizen of the United States, and resident of Appleton, in the county of Outagamie and State of Wisconsin, have invented new and useful Improvements in Fourdrinier-Wire Stretchers, of which the following is a description, reference being had to the accompanying drawings, which are a part of this specification.

This invention has for its object to provide an improvement in Fourdrinier wire stretching machines whereby the wire fabric may be subjected to a sufficient tension to take up the slack in its edges incident to the weaving operation without danger of injuring the seam.

Heretofore it has been customary to stretch a Fourdrinier wire to a limited degree, but in cases where the loom work has left a great amount of slack along the edges of the cloth it has not been feasible to subject the fabric to such a degree of tension as to take up the slack at the selvages, owing to the liability of pulling the seam apart in so doing. By means of the improvements constituting the present invention the stretching may be continued until it amounts to about twice the amount that has heretofore been considered safe, thus taking up a greater amount of slack in the edges than has been possible with safety heretofore, and without injury to the seam. This permits of the correction of extreme slack conditions so that both sides of the wire may be stretched to the same length without undue slack at either edge.

A further object of the invention is to protect the seam from injury during the stretching operation by embedding the knuckles on either side thereof in a yielding or impressionable bearing surface so as to relieve the seam of strain, as by placing a sheet of rubber or leather around the stretching roll on which the seam is positioned.

With the above and other objects in view the invention consists in the Fourdrinier wire stretcher as herein claimed and all equivalents.

Referring to the accompanying drawings, in which like characters of reference indicate the same parts in the different views,

Figure 1 is a side view of a Fourdrinier wire stretching machine provided with the improvements of this invention, with a part broken away;

Fig. 2 is a plan view thereof;

Fig. 3 is a fragmentary end view showing the seam positioned on the stretching roll with the protecting material therebetween; 60

Fig. 4 is an end view showing part of the other end of the machine;

Fig. 5 is a sectional view of the stretching roll showing the protecting material thereon; and, 65

Fig. 6 is a similar view showing the seam in position for being rolled.

In these drawings 10 indicates suitable legs or supports on which are mounted the heavy longitudinal side beams 11 which are 70 connected at regular intervals by cross pieces 12 resting on bracket extensions of the legs, there being a heavy table 13 mounted on the cross pieces 12 and extending from one side beam 11 to the other and from one end of the 75 frame to the other. The side beams 11 rise above the level of the table 13 and at one end are provided on their top surface with upstanding dovetail guide flanges 14, on which are slidably mounted bearing blocks 15 forming open bearings to receive the trunnion-like ends of a shaft 16 carrying a wooden roll 17. Slides 18 are also slidably mounted on the guide flanges 14 and have upstanding flanges 19 with gravity pawls 20 pivotally 80 mounted thereon and dropping into engagement with rack teeth 21 in grooves of guide flanges 14. An I-beam 22 turned on its side rests on the slides 18 and against the flanges 19 thereof and is adapted to bear at its head 90 against the roll 17.

At the other end of the machine the beams 11 have dovetail grooves 23 at their upper edges in which are slidably mounted hook-like open bearings 24. In said bearings are 95 journaled the trunnion-like ends of a shaft 25 on which a stretching roll 26 is mounted. Bearings 27 fixed on the beams 11 have jackscrews 28 threaded through them, and an I-beam 29 which is turned on its side and slidably rests on the side beams 11 is engaged by the jackscrews 28 and bears against the stretching roll 26.

In order to stretch a Fourdrinier wire the rolls 17 and 26 are inserted therein and then mounted in their bearings. The I-beams 22 and 29 are then placed in position and the roll 17 is forced rearwardly as far as it will go to take up the slack in the wire, the pawls 20 engaging the rack teeth 21 to 105 hold the slides 18 in a position for maintaining this adjustment. The stretching

roll 26 is then advanced by turning the jackscrews 28, the jackscrews forcing the I-beam 29 against the roll 26, thus causing the bearing slides 24 to slide in the dovetail guide 5 grooves 23. This movement of the stretching roll 26 places the wire cloth under tension and stretches it until the undesirable slack at the edges is compensated for by an elongation of the central portion, the seam 10 being centrally positioned on the stretching roll to relieve it as much as possible from the strain. When the slack in the edges of the wire is excessive there is danger in attempting to stretch the wire without giving 15 additional protection to the seam, for the strain on the seam will cause it to break. I therefore provide a protector consisting of a flexible blanket 30 of sheet rubber or leather which is wrapped around the stretching roll 26 before the latter is inserted in the endless belt of wire fabric. When the seam 32 of the wire fabric is centrally positioned on the stretching roll 26 with the impressionable protecting sheet 30 between 20 the fabric and the roll the stretching operation causes the knuckles of the wires of the fabric on each side of the seam to become deeply embedded in the protecting sheet, thus relieving the stitching wire of the seam 25 from the strain to a large extent and permitting a greater tension to be applied to the fabric without injuring the seam than would be possible without the presence of such protecting sheet. After a wire has been 30 stretched the seam is rolled and a metal strip 31 is embedded in the stretching roll 26 to form the anvil or hard bearing surface against which the seam is placed in the manner shown in Fig. 6 for the performance of 35 this rolling or flattening of the seam by the use of a metal roller not shown.

As a usual thing all Fourdrinier wires have slack edges. It is preferred that they should be slightly slack, or in other words, 40 not as tight as the body of the wire. If they are as tight as the body of the wire they will have a tendency to crack at the edges. In the ordinary process of weaving some wires are quite slack at the edges, and some not 45 so much, but all wires have edges sufficiently slack to necessitate stretching to bring them up or remove the slack. This has caused more or less trouble because wires that had slack edges required considerable stretching 50 and it was impossible to give them the required amount of stretching because of the seam being pulled open too much. In using the protecting sheet, however, the wire is stretched to the point where rolling the seam 55 is necessary, and then the rubber or leather protecting sheet 30, which is preferably about one-sixteenth of an inch thick and of sufficient width and length to cover more

than half of the diameter of the stretching roll, is placed between the wire cloth and the stretching roll, the seam being positioned in the middle of the stretching roll so that there is as much strain on one side thereof as there is on the other. At the points where the wire cloth comes in contact with the sheet rubber it will embed itself therein under the severe strain to which the cloth is subjected and will not stretch perceptibly because of the reinforcement or resistance to stretching that is offered by the rubber 75 protecting sheet, and the seam is not damaged in the least through overstretching.

As before stated, it has heretofore only been possible to stretch a wire a very limited amount, but through the use of this rubber sheet it is possible to stretch it twice as much, and by doing so the wire is properly stretched and it is easy to get the wire square and at the same time bring the edges up so that they are sufficiently tight to answer requirements.

It is obvious that the sheet of protecting material need not be of rubber or leather but may be of any impressionable, flexible material that will reinforce the fabric and relieve the wires on opposite sides of the seam from the strain of the stretching tension.

What I claim as new and desire to secure by Letters Patent is:

1. In a Fourdrinier wire stretching machine having a fixed roll and a movable roll around which the Fourdrinier wire fits, a sheet of rubber placed upon one of the rolls and adapted to have the seam of the fabric centrally positioned thereon to permit the 95 knuckles of the fabric on both sides of the seam to become indented therein to relieve the seam from strain during the stretching operation.

2. In a Fourdrinier wire stretching machine, a pair of rolls upon which the wire fabric is placed and one of which is adapted to be moved with relation to the other to stretch the fabric, one of said rolls having a resilient surface in which the knuckles of the wire on either side of the seam may become embedded to relieve the seam of strain during the stretching operation.

3. A machine for stretching Fourdrinier wire, comprising a fixed roll and a movable 105 roll around which the Fourdrinier wire fits, and a removable impressionable covering adapted to be interposed between one roll and the seam portion of the Fourdrinier wire to have the knuckles of the wire on either side 110 of the seam become indented therein to relieve the seam from strain during the stretching operation.

In testimony whereof, I affix my signature.

ALBERT B. WEISSENBORN.
